(57) **CLAIM**

The ornamental design for a display screen with a transitional graphical user interface, as shown and described.

DESCRIPTION

FIG. 1 is a front view of a first image in a sequence for a display screen with a transitional graphical user interface; FIG. 2 is a front view of a second image thereof; FIG. 3 is a front view of a third image thereof; FIG. 4 is a front view of a fourth image thereof; FIG. 5 is a front view of a fifth image thereof; FIG. 6 is a front view of a sixth image thereof; FIG. 7 is a front view of a seventh image thereof; and, FIG. 8 is a front view of an eighth image thereof.

The broken line showing of a display screen forms no part of the claimed design. The broken lines of text, numbers, icons, and boxes demonstrating portions of a graphical user interface displayed on the display screen in all views form no part of the claimed design. The areas filled in with stippling dots illustrate contrasting appearance and form a part of the claimed design. The areas filled in with fill lines illustrate an additional-contrasting appearance of a background fill, and form a part of the claimed design.

The appearance of the image sequentially transitions between images shown in FIGS. 1 through 8. The process or period in which one image changes to another forms no part of the claimed design.
